PROCESS OF APPLYING MATERIAL TO A
SHEET OR WEBWilliam F. Grupe, Lyndhurst, N. J., assignor to
Chambon Corporation, Garfield, N. J., a cor-
poration of New York

Application August 19, 1936, Serial No. 96,836

4 Claims. (Cl. 91—70)

The invention relates to an improved process of applying material to a sheet or web.

The present invention is directed to the applying upon a sheet or web, material of suitable 5 character which is solid at atmospheric temperatures, but applied in fluid status at an elevated temperature.

Heretofore, material has been applied to sheet or web through the instrumentality of a smooth 10 faced roller which is in contact with the sheet or web under pressure of sufficient degree to effect positive contact between the sheet or web and the applied material. However, such procedure has many disadvantages and particularly 15 in that the amount of the applied material and uniformity thereof are difficult to control, further, that the pressure between such smooth faced roller and the sheet or web causes the applied material to be forced into the pores of the 20 sheet or web, and frequently through the pores of the sheet or web, thus necessitating a higher quality and higher priced sheet or web material.

Pursuant to my invention, the above stated and other difficulties of the prior art, are overcome 25 by the employment of an intaglio roller as the instrumentality of application of the applied material. By such means the desired predetermined and measured amount of the applied material is supplied and deposited upon the sheet or 30 web independently of the pressure between the face of the intaglio roller and the sheet or web and direct contact between the applied material and the sheet or web is had without forcing the applied material into the sheet or web. The distribution of the material applied is thus directly 35 controlled and deposited upon the sheet or web.

My invention further contemplates the employment of applied material which is solid at atmospheric temperatures, and which is supplied to 40 the applying intaglio roller at elevated temperature to render such applied material fluid at the stage of application.

Materials applicable for carrying out my invention are of variant character depending upon 45 the nature of the coating or printing desired. For example, waxes, resins, pitches, gums, etc., either natural or synthetic, employed either singly or in combination with one other, having melting points at suitable elevated temperatures with 50 respect to atmospheric temperatures, may be employed. For attaining color effect, media such as pigments, dyes or other coloring, inclusive of white, may be dispersed in the above referred to natural and/or synthetic materials serving as 55 the vehicle.

My invention has particular application to the coating or printing as aforesaid upon a web such as paper, cellulose films such as "Cellophane" and other cellulose sheeting, metal foils, metal sheets, etc., fabrics and the like either in single 5 or multiple stage of application.

Supplemental to the primary control by the intaglio characteristics of the intaglio roller of the amount and uniformity of the applied material, variant effects of the applied material are 10 produced by regulation of the temperature of the web at the stage of application of the material and/or prior thereto and/or subsequent thereto. Such thermal treatment may be for the purpose of elevating the temperature of the web, of lowering the temperature of the web, or of maintaining the temperature of the web at atmospheric, i. e. room temperature. By such thermal regulation control is had with respect to penetration and extent thereof or non-penetration 15 of the applied material relative to the web and/or with respect to the blending of successive applications of applied material having different characteristics as to color or other physical attributes.

Subsequent to a single stage application or 20 subsequent to the first or other application stage of a succession of application stages, the web and thereto applied material or materials may be further thermally treated to attain rapid hardening of the applied material and the prevention of penetration of the applied material 25 relative to the web or the control of the penetration to any desired degree of the applied material into the web, or in the instance of multiple preceding applications of applied materials the 30 control of blending and/or intermingling of the respectively applied materials.

Among other advantages attained by my invention are the savings in materials in that by the usual method of intaglio printing the printing 40 material must be brought to a fluid state by solution in solvents, with the attendant necessity of wastefully disposing by evaporation of these solvents after the printing material has been applied to the web; the reduction of the time period 45 required for the solidification or drying of the printing material after its application to the web since the hardening or drying of my material is brought about simply and rapidly by the lowering of its temperature to atmospheric temperature 50 which may be accelerated by the application of circulated, preferably chilled, air or by contact with a chilled surface such as a roller; further, by my method, the full, i. e., unextended body 55 of the applied material is applied directly to the

web whereas in solvent applied printing material but a relatively small fractional proportion of the applied printing material, usually in the neighborhood of 30%, can be of a solid nature, 5 the balance being solvents which must be waste-fully dissipated. Additionally, by my process the applied material when desired, is applied solely to the facial plane of the web, whereas in the case of solvent applied printing material, the solvent, together with entrained portions of the 10 printing material, may penetrate the web interiorly of the facial plane of the web.

Further features and objects of the invention 15 will be more fully understood from the following detail description and the accompanying drawings, in which:

Fig. 1 illustrates diagrammatically, largely in vertical section, a two-stage procedure in carrying out my invention, embodying in particular a heated reservoir for the supply of the applied material and a heated intaglio applying cylinder.

Fig. 2 illustrates diagrammatically, largely in vertical section, a one-stage procedure in carrying the invention.

Fig. 3 illustrates diagrammatically, largely in vertical section, another form of two-stage procedure in carrying out the invention.

Fig. 4 illustrates diagrammatically, largely in vertical section, another form of two-stage procedure in carrying out the invention.

Referring to the two-stage procedure illustrated in Fig. 1, the web, such as paper, cellulose film, i. e., "Cellophane" or other cellulose sheeting, metal foil, metal sheet, fabric, etc., is indicated at 10. The material indicated at 11, to be applied to such web 10 is supplied from a suitable reservoir indicated at 12. Such material 11 may be a wax, resin, pitch, gum, etc., either natural or synthetic, employed either singly or in suitable combination having melting points at temperatures suitably above atmospheric temperatures, and which may or may not embody suitable coloring media, such as a pigment, dye, etc., inclusive of white, suitably dispersed within the stated material 11. Desirably, such reservoir 12 is provided with suitable heating means, indicated at 13, for maintaining the temperature of the contained material 11. Such heating means 13 may be of electrical character or piping for conveying a suitable heating medium.

Such material 11 is suitably supplied to the intaglio cylinder indicated at 14 which is maintained at a suitable elevated temperature by suitable heating means indicated at 16. Such heating means 16 may be of electrical character or piping for the conveyance of a suitable heating medium.

The direction of rotation of the intaglio cylinder 14 is indicated by the arrow 16. At 17 is indicated a scraper, doctor blade, or the like, bearing under pressure against the surface of the intaglio cylinder 14, as is well understood by those skilled in the art.

The impression cylinder, in association with the intaglio cylinder 14, is indicated at 18, and its direction of rotation is indicated by the arrow 19. Such impression cylinder 18 may, if desired, be provided with heating means, indicated at 20, which may be of the character of the aforesaid heating means 13, 15.

The two-stage procedure illustrated in Fig. 1 is typical of the utilization of my invention for multiple application of applied material, either the same or different, at the respective stages, 75 such materials being applied to the web either in

superimposition or in register with one another. The above described parts appear in Fig. 1 at the left of Fig. 1 and indicate the employment of such parts at the first stage of application of the desired material 11. At the right of Fig. 1 are indicated parts corresponding to the above described parts, the various reference characters corresponding thereto with the suffix *a*, applicable for the applying of the same or different material 11*a*, of the above general character, either in superimposition of the impression effected by the first stage intaglio cylinder 14 or in register therewith.

Such two-stage treatment, pursuant to my invention, as to certain phases thereof, is facilitated by the employment of a suitable thermal device indicated at 21, which may be either to elevate the temperature of the applied material as for the purpose of inducing the penetration into the web 10 of the material 11 applied by the intaglio cylinder 14 or to lower the temperature, such as by chilling the material 11 and the web 10, for the purpose of rapid setting of the applied material 11. At 21*a* is indicated a thermal device, which may be of temperature-elevating character or temperature-reducing character, for controlling the extent of penetration of the applied material 11*a* or conjointly of the applied materials 11, 11*a*.

At 22, in Fig. 1, is indicated one or more breaker 30 rolls or the like, employed for controlling the path of travel of the web 10, and, as indicated more fully hereinafter, may be equipped with a suitable thermal device, for the regulation of temperature of the web 10 and the thereto applied material 11. 35

The arrangement shown in Fig. 2 is typical of the utilization of the invention for a single stage treatment of a web 10, pursuant to my invention. The supply of suitable material 11 may be had by the parts and associated devices corresponding to 40 those indicated at the first stage of the two-stage procedure illustrated in Fig. 1, which parts and appurtenant devices are designated by corresponding reference characters. The procedure indicated in Fig. 2 particularly illustrates the 45 pre-cooling of the web 10 by a suitable cooling device indicated at 23. In certain phases of my invention the impression roller 18 may be un-heated. Fig. 2 also illustrates the cooling of the web 10 after application thereon of the treating 50 material 11 through the instrumentality of the intaglio cylinder 14, such cooling treatment being had by a suitable cooling device indicated at 21. Supplemental cooling of the treated web 10 may be had by providing the breaker roller 55 22*a* with suitable cooling means indicated at 24.

Fig. 3 illustrates a further embodiment of my invention, as carried out by two-stage procedure. The parts corresponding to those indicated in Fig. 1 are designated by like reference characters. The arrangement shown in Fig. 3 illustrates in particular the pre-thermal treatment of the web 10 by a thermal device indicated at 23, either of heating or cooling character, the thermal treatment of the web 10 having applied thereto the material 11 through the instrumentality of the intaglio cylinder 14 and its impression cylinder 18, the thereto subsequent thermal treatment of the web by the thermal device 21, 70 and the application at the second stage of the treating material 11*a* through the instrumentality of the intaglio cylinder 14*a* and its associated impression cylinder 18*a*, and the final thermal treatment of the superimposed or registered dual 75

impressions of the materials 11, 11a, by the thermal device indicated at 21a.

Pursuant to the procedure in Fig. 3, the respective impression cylinders 18, 18a, and/or the breaker roller 22 may be unheated or provided with suitable cooling means.

In the arrangement illustrated in Fig. 4, like parts being indicated by like reference characters corresponding to the above described parts, the web 10 may be cooled or heated by the indicated thermal device 23 in advance of the first stage application of the material 11, at which stage the impression roll 18 may be equipped with suitable heating means indicated at 20, similarly as above. The thus treated web 10 and material 11 applied thereto may be thermally treated by a suitable thermal device indicated at 21, then passed over a breaker roller 22, which may be equipped with a suitable thermal device indicated at 24, and then treated at a second stage, with suitable material 11a, either in superimposition of the first stage application or in register therewith, which may be further objected to suitable thermal treatment indicated by the thermal device 21a.

As appears from the above, the number of stages of application of material of the above character, and thermal treatments thereof, may be as desired.

By my invention, as appears from the variant forms thereof as above pointed out, variant products as desired are attained, inclusive of variant color effects. For certain types of web, control with respect to penetration of the applied material is had by proper control of the temperature of the web; again, such control of penetration of the applied material is regulated by the temperature of application of the applied material controlled by the temperature of the bath of the applied material and/or the temperature of the intaglio cylinder, supplemented where desirable by the controlled temperature of the impression cylinder and further subject to control by a suitable thermal device or devices.

The above procedure, in the practical arts, is applicable to variant types of applied material of the character set forth hereinabove, for variant extents of coverage of the facial area of the web, for variant outline of application with or without variant color effect.

The invention is of particular utility in the manufacture of carbon tissue, in which character of utilization of the invention the desired transfer medium, such as the above referred applied material, particularly waxes, resins, pitches, gums and coloring material, is applied in uniformly controlled quantities and uniformly controlled penetration and controlled superficial deposit, either in desired segregated facial area or co-extensive with the face of the web. By applying uniformly controlled quantities of the same or varied compositions of applied material in multiple superimposed layers and my proper thermal regulation of the respective layers, carbon tissue having superior transfer and retention characteristics is obtained.

The invention may be employed for applying segregated areas of the above stated material, to serve as areas bearing adhesives serving upon blanking of the web to bond overlapping areas and the like.

Whereas, I have described my invention by reference to specific forms thereof it will be understood that many changes and modifications may be made without departing from the spirit of the invention.

I claim:

1. The process for the production of carbon transfer paper, which comprises applying to a surface of a web of paper by means of a heated intaglio roller and a cooperating heated impression roller, a thermoplastic base transfer material heated to a liquid state; thereafter thermally treating the said surface as the web of paper travels; subsequently applying to said surface, by means of a heated intaglio roller and a heated cooperating impression roller, a pigment-carrying-material heated to a liquid state; and finally thermally treating the so treated web.

2. A method of treating a web of sheet material with coating material which is liquid when heated and solid when cooled, comprising applying to a surface of said web of sheet material, by means of a heated intaglio roller and a cooperating heated impression roller, thermoplastic coating material heated to a liquid state; thereafter thermally treating the said surface as the web of sheet material travels; subsequently applying to said surface, by means of a heated intaglio roller and a cooperating heated impression roller, further coating material heated to a liquid state; and finally thermally treating the so-treated web.

3. A method of treating a travelling web with a marking or coating material which is liquid when heated and solid when cooled, comprising heating at least one surface of the web; applying the material, heated to a liquid state, in predetermined measured amounts to the surface of the web by means of an intaglio roller and a cooperating impression roller, said intaglio roller being immersed in a bath of the heated material; thereafter thermally treating the surface as the web travels; subsequently applying further predetermined amounts of material, heated to a liquid state, to said surface by means of a heated intaglio roller which is immersed in a heated bath of the material and has a cooperating impression cylinder; and finally thermally treating the so treated web.

4. A method of treating a traveling web with a marking or coating material which is liquid when heated and solid when cooled, comprising heating at least one surface of the web; passing said heated web between an intaglio cylinder and a cooperating impression cylinder, said intaglio cylinder being immersed in a heated bath of the material and heated uniformly, whereby said material will be applied to the web in predetermined quantities; and subsequently cooling the applied material.

WILLIAM F. GRUPE. 65
